CLAIM

The ornamental design for a therapy plate with LEDs as shown and described.

DESCRIPTION

FIG. 1 is a perspective view of a therapy plate with LEDs showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the therapy plate with LEDs shown within the area designated as **9** in FIG. 1;

FIG. 10 is an enlarged view of the therapy plate with LEDs shown within the area designated as **10** in FIG. 2;

FIG. 11 is a perspective view of the therapy plate with LEDs in a second state; and,

FIG. 12 is a perspective view of the therapy plate with LEDs in a third state.

The short-dash broken lines immediately adjacent to shaded areas represent boundaries of the claimed design. In FIG. 12, the dash-dash broken lines depicting a middle panel and two connecting components illustrate unclaimed environment. All other dash-dash broken lines illustrate portions of the therapy plate with LEDs that form no part of the claimed design. The dot-dash broken lines in FIGS. 9-10 show the boundary of the enlarged view and form no part of the claimed design.
